J. Q. CLARKE.
FARROWING HOUSE.

APPLICATION FILED FEB. 17, 1912.

1,039,255.

Patented Sept. 24, 1912.

UNITED STATES PATENT OFFICE.

JOHN Q. CLARKE, OF CRAWFORDSVILLE, INDIANA, ASSIGNOR TO THE J. Q. CLARKE
TANK CO., INCORPORATED, OF CRAWFORDSVILLE, INDIANA.

FARROWING-HOUSE.

1,039,255.

Specification of Letters Patent. Patented Sept. 24, 1912.

Application filed February 17, 1912. Serial No. 678,326.

To all whom it may concern:

Be it known that I, JOHN Q. CLARKE, residing at Crawfordsville, in the county of Montgomery and State of Indiana, have invented a new and Improved Farrowing-House, of which the following is a specification.

This invention is in the nature of an improved farrowing house, and my said invention has for its object to provide an application of the character mentioned of a very simple and inexpensive construction, and in which special provision is made for easily letting sunshine through the top of the house, in which the structure is such that the sow is kept from laying on the brood and easy access for getting to the sow is provided for.

With other objects in view that will hereinafter appear this invention comprises a farrowing house that embodies the peculiar construction and novel arrangement of parts hereinafter fully explained, specifically pointed out in the appended claims and illustrated in the accompanying drawing, in which:—

Figure 1 is a perspective view of my improved farrowing house, looking at the entrance side thereof. Fig. 2, is a similar view looking at the rear side thereof, the slidable top being at the open position. Fig. 3, is a horizontal section taken substantially on the line 3—3 on Fig. 1. Fig. 4, is a section on the line 4—4 on Fig. 2.

In the practical arrangement, my farrowing house is built of sheet metal and in the form, as shown, it comprises a flat bottom ring 1, having an annular flanged rim 10, at the inner edge thereof. The body of the house includes an annular wall 3, also of sheet metal and the form shown is a single member, the lower edge of which laps against and is fastened to the bottom flange 10. The upper end of the wall 3 is riveted, or otherwise fastened, to an annular flange 5, which has an integral outwardly and downwardly extending rim 50 the purpose of which will presently appear. The side wall of the house has a large opening 9 that extends the full length thereof and the said opening is formed by bending one end of the wall 3 inwardly to extend over and beyond the opening 9. The wall 12 is curved inwardly, and by reason of its extension a side passage or entrance 7 is formed that com-

municates with the main or huddling compartment 70, as is clearly shown in Figs. 1 and 3. To avoid injury to the brood, in passage into the entrance 7, the edge 30 of the wall is bent outwardly to form a flat 60 face 31. For strengthening the blind wall, upper and lower angle braces 13 and 14 are provided, the lower one of which extends across and connects with the ring flange 10.

62 designates a sheet metal top, preferably cone shaped, the lower edge 63 of which lies flatwise on and is riveted to the rim 50. The upper point of the top has a cap plate 65 that carries a centrally located stud pin 8. The top has a large triangular 70 opening regulated by a triangular cover section 64 movably mounted to slide onto the fixed top portion and to be slid over the opening 66, and for holding the cover in operative position on the top, the upper end 75 thereof has a strap 68 apertured to ride on the stud pin 8, and the lower end has clips 69 that ride over the edge of the rim members 50 as is clearly shown in Fig. 4.

By reason of the peculiar construction of 80 parts as described, and shown, a practical, economical and easily handled farrowing house is provided, which affords great protection for the brood, since the blind wall not only acts as a storm and wind shield, 85 but also divides the interior of the house into a passageway and a huddling compartment, and since the house has a circular shape, the sow is practically kept from laying on the brood. The large opening in the 90 top provides for admission of sunshine and air to the huddling compartment. By reason of the detailed arrangement of the parts, the metal portion can be readily shipped in a knocked-down condition, and assembled 95 as desired.

An important advantage in my construction of hog house is the huddling brood is out of line with the opening 9 and thoroughly protected against rain, when the top 100 opening is closed, and by having the large opening in the top, the sow can be easily got at.

What I claim is:—

1. A farrowing house composed entirely 105 of sheet metal and including a single sheet bent to form the vertical wall of the housing, one end of the said sheet being bent inwardly across and beyond its adjacent end whereby to form an entrance opening and a 110

passage that extends beyond the said opening, and a top that extends entirely over the housing mounted on the upper edge of the said housing.

- 5 2. A farrowing house comprising lower and upper angle rims, and transversely extended angle rims that connect with the opposite inner edges of the said upper and lower rims, a housing formed of a single 10 sheet of metal, the upper and lower edges of which engage and are secured to the top and bottom rims, one end of the said single sheet being bent inwardly and transversely

over and beyond the other edge of the said sheet whereby to form a blind wall and a 5 passage that extends beyond the said other edge, the upper and lower edges of the said inwardly extended end engaging and being secured to the transversely extended upper and lower angle rims and a top closure for 20 the housing mounted upon the upper angle rim.

JOHN Q. CLARKE.
